UNITED STATES PATENT OFFICE.

ARTHUR A. VARDELL, OF DALLAS, TEXAS; HIGHLAND GEE VARDELL EXECUTRIX OF
SAID ARTHUR A. VARDELL, DECEASED.

MECHANISM FOR REMOVING USEFUL FIBER FROM SEEDS.

1,426,687.

Specification of Letters Patent. Patented Aug. 22, 1922.

Application filed August 22, 1919. Serial No. 319,105.

To all whom it may concern:

Be it known that I, ARTHUR A. VARDELL, a citizen of the United States of America, and resident of Dallas, in the county of Dallas 5 and State of Texas, have invented new and useful Improvements in Mechanism for Removing Useful Fiber from Seeds, of which the following is a specification.

This invention relates to the general class 10 of machines adapted to remove fibers from their attachments, such as gins, cotton seed linters, wool-burring machines and the like.

Machines of this type are broadly alike, but for cotton the operation is customarily 15 carried out in two stages, the gin proper being relied upon to remove the long-fibred cotton from the seed and the linter [or de-linter] gin being employed to work upon the cotton seed, the product of the gin 20 proper, to remove from it the short adherent fibers. The gin proper and the linter gin differ from each other essentially only in the adjustments, proportions or dimensions of the parts appropriate to their specific duties. This invention has particular 25 reference to means for the recovery of fiber or particles, applicable to saw gins for either use and to other machines.

All saw guns as heretofore constructed deliver 30 a great volume of air as an incident of the construction and operation of the doffing brush forming an essential part of the gin. This air, charged with fine particles of lint and dust, when delivered into the room, 35 menaces the health and efficiency of the operators, and constitutes a serious fire risk. I am aware of attempts to minimize these risks by connecting the individual gins to deliver into a common conveyor, or by air-doffing the saws by separately generated 40 blast or suction currents, or by other expedients, none of which are wholly successful for this purpose.

In the best practice of which I am aware 45 in the prior art, pneumatic doffing, or the common collection of fiber by delivery into a common flue or conveyor has resulted in unnecessary expenditure of power, often amounting to four or more horse-power per 50 gin. The rotating elements of the gin itself

expend much power in moving with them a great volume of air.

When external pneumatic means heretofore have been employed the air-moving effort of the elements of the gin has been 55 retained, with resultant waste of effort.

So far as I am aware, the operation of prior gins and linters also has been defective in failure to prevent removal with the seed of a proportion of the fiber actually 60 separated by the gin saws, and in failure properly to separate from the good lint a large portion of motes capable of such separation during the removal of the fiber from the seed, and difficult or impossible to remove 65 at a later stage of treatment. Loss has also been occasioned whenever access to the saws became necessary, such access involving waste of the whole contents of unginned material in the roll-box. 70

Principal objects of this invention are to provide for the complete and economical recovery of the fiber separated from the seed by the gin, to separate from the fiber a maximum percentage of motes and impurities, 75 and to provide a gin or linter adapted to operate without delivering into the workroom a stream of air containing dust and fiber from the material being ginned; to reduce the volume of air carrying the fiber, 80 and to provide for pneumatically conveying and delivering fiber from a fiber-removing implement, such as a gin saw in an improved manner. Further objects are to provide in a gin or linter gin for the improved 85 separation of motes from the product, to provide for the improved separation from the saws of a saw gin of fibers and thereby to save lint heretofore wasted, to provide for separating from the lint and removing from 90 each gin a large proportion of the dirt, sand, leaf-scrap and other waste; and for these purposes to provide a gin economical in power and adapted to be maintained in adjustment during long wear without replacement of parts and arranged for access to the working parts without loss of the unginned material in the gin. 95

The invention comprises a new relation of the doffer element of such gins to the saw 100

or other fiber remover, and a new relation to these elements of the gin of the means employed for removing motes and impurities from the useful fiber, as well as an improved 5 construction of ginning apparatus characterized by compactness, durability and improved capacity for access to the parts and for adjustment.

I have elected to illustrate the genus comprised in the invention by an example of one 10 species for use as a linter gin as shown in the accompanying drawings, in which—

Fig. 1 is a vertical central section of a linter gin according to the invention;

15 Fig. 2 is a similar view illustrating another position of the parts; and

Fig. 3 is a longitudinal section of a doffer brush employed in the new relation.

In the preferred form of my device shown 20 I have illustrated one instance of a new genus of saw gins in which an improved relation of the doffer brush to the saws, based upon observation of a mode of operation of such brushes not heretofore sub- 25 scribed to by those skilled in the art is utilized to improve both the working conditions of ginneries and the economy of the recovery of fiber. It has heretofore been believed that the air-current set up by the 30 rotating gin brush employed to doff the useful fiber from the saw cylinders is essential to the function of the brush as a doffer. It has also been believed that a relatively slight interengagement of the brush with 35 the space between the individual saws of the saw cylinder was the best arrangement, and the losses of fiber heretofore observed due to the return of useful fiber into the seed cotton or between the bars of the grate, 40 thence to pass out through the seed-gate, have been accepted as inevitable. In the present gin a deeper engagement than usual of the brush with the saw is employed, a much smaller brush than usual is preferred, 45 and the function of the brush to move a current of air, while utilized, is no longer exclusively relied upon to create such air currents as are needed in the gin, the brush being designed to have as little function as 50 a fan as possible, the conveying movements within the gin being controlled by suction currents exteriorly created. In one aspect the invention relates to a rearrangement of the gin in respect to these air currents where- 55 by heretofore lost fiber is recovered, and waste of effort avoided. In another aspect the invention is directed to the reduction of the volume of air moved by the gin brush, heretofore thought to be unavoidable 60 and heretofore permitted to create in the surroundings of the gin a bad condition due to escape of air laden with fiber and with dust blown out of the gin by the operation of its elements. The present gin not 65 only recovers all of the fiber but avoids the

pollution of the air of the place in which it is installed by the device of inducing inward currents of air into the machine and its connections everywhere it is open to the air of the room, the only air-current leaving 70 the gin being a suction current conveying away the relatively pure lint in a closed flue. This current is of very greatly less volume than the air-current blown away from the gin in the ordinary operation, and 75 may be of correspondingly higher velocity and be carried by a smaller flue, operating to convey the fiber with less consumption of power than is required by the usual arrangement of gin-parts working as a fan 80 and blowing a larger volume of air at a lower velocity away from the gin.

Referring to the drawings, the machine frame as usual may comprise uprights 1, side panels 1^a, and wooden or metal longitudinal struts 1^b, 1^c, 1^d, etc., the end frames comprising the uprights 1 and transverse members 1^e having thereon bearings for a saw shaft 2 having if desired, adjustments permitting the shaft 2 to be raised or 90 moved as wear and recutting of the saw-cylinder made up of shaft 2 and saws 10 reduces the diameter of the cylinder, which may be driven as usual. The longitudinal frame member 1^c may carry any preferred 95 feeder hopper 12 and bearings and actuating means for feeder roll 13, feeder gate 14, and other desired adjuncts of the feeder mechanism. The pivoted breast 8, presently referred to, may as usual carry a grate 9 and a float roll shaft 6.

A doffer brush 5 rotating with a driven shaft 3 on bearings presently to be mentioned, is so arranged to bring the shaft 3 beneath and but little behind the vertical 105 from the center of saw-cylinder 2, so that contact of the saws 10 with the brush 5 occurs near [or much nearer than usual to] the bottom of the saw cylinder, for purposes which will presently appear.

The disposition of the brush with respect to the saw cylinder enables the centrifugal throw of the saw cylinder, by which the motes and heavy impurities are thrown off, to be utilized to separate these motes from 115 the fiber clinging to the saws. The prior art procedure has been to deposit the motes on the doffing-brush and then to rely upon the centrifugal throw of the doffing-brush and the air-current induced by it to separate the motes from the fiber. This is fundamentally bad practice, since when once engaged with the fiber mat carried by the doffer-brush, the separation of the motes can not be thoroughly effected.

The machine comprises a mote-deflector 20, preferably mounted for rotatable adjustment on a longitudinal strut 21, by means of a slotted sector 22 on deflector 20, and a bolt 23 in the end panel 1^a. The 130

point 24 of deflector 20 when adjusted is near the periphery of the saws and behind them as shown. The mote deflector is imperforate and extends the width of the saw 5 cylinder, its lower edge being in substantially air-tight contact with a partition 26 constituting a back-seal above and behind the deflector 20 and the saws 10, and extending from the longitudinal 1° to a brush-10 casing 37 presently mentioned. Ends 27 bolted to one of the uprights 1 complete the enclosure of a moting chamber 28, preferably having a trough 26^a at the bottom for a screw mote-conveyor 30 delivering into 15 a chute 31.

The air currents flowing in the neighborhood of the mote deflector are important to its function. The gin is therefore arranged so that that part of the saw cylinder between 20 the grate-fall and the mote deflector works in the controllable air-space 28 protected by back seal 26 which is provided with an air inlet opening 32 adapted to be regulated in any convenient way, as by a 25 sliding regulator damper 33 controlling air inlet openings 32. One section of back seal 26 may be hinged at 34, and held closed by hand-screws 35. The sealing of the spaces back of the gin brush is completed 30 by vertical flexible baffles of leather, rubber or the like on the end-panels 1^a, one of which is shown at 36 in contact with the ends of the saw cylinder and extending from longitudinal 1° to the front upright 1. A 35 concave brush-casing 37 surrounds and stands in, or nearly in, contact with a long section of the periphery of the brush. Casting 37 is related to the variable position of the brush shaft 3 as presently explained.

40 Instead of the brush as usual being arranged to have a fanning action by being built up of longitudinal rows of bristles, the brush 5 may be solid, or [as shown in Fig. 3] consist of annular rows of bristles, each 45 row having tufts arranged to engage at each side face of each saw.

Referring to Fig. 3 the brush 5 may consist of separator disks 5^a of hard fiber, wood or metal strung on an enlargement 3^a of 50 shaft 3 threaded at 3^b to receive compression nuts 5^b, the disks 5^a having therein turned grooves 5^c to receive annular brush-tuft strips 5^d between which the radial tufts 5^e are held. The brush strips may be 55 fiber, metal or paper, and the thickness of the separator disks may, as shown, be the distance between the saws 10, or a divisor of this distance. In the latter case, there are rows of tufts between the saws, 60 available for use by shifting the shaft 3 endwise.

The tufts 5^e run in line with the saws 10, some of their bristles wiping each side of the saw. The whole diameter of the 65 brush may be, and preferably is, much less

than in usual practice. Such a brush may be rotated at the usual speeds of from 1000 to 1200 R. P. M. without blowing a strong air-current thereby.

For adjustment purposes the brush is 70 mounted in bearings, not shown, carried by and vertically adjustable on vertical slides 40 in ways 41, 41, on the frame, each slide having integral lugs 44 straddling a spanner nut 45 on a screw 46 fast in a lug of 75 the guide plate 41 bolted to the end frames. By turning the nut 45 the brush 5 and the casing 37 are adjusted vertically together.

The lint is carried away from the gin through a lint trunk 50, preferably made 80 as a curved pipe of flat rectangular cross-section, having flanges 51 bolted to channel beams 52 carried by the plates 40. The delivery end of this lint trunk takes into an opening 54 in a casting 55 bolted to the 85 gin frame, and provided with screws 56 in openings in a flange 57 fastened to the lint trunk 50, for initial adjustment of trunk 50 with plates 40. Attached to the casting 55 a transition pipe 59 delivers into the main 90 suction conveyor conduit 60. A hand-valve 61 may be arranged in a casing 62 forming the upper end of transition 59, and suitably supported on a frame-member of the machine as shown at 1^d. A lint trunk nozzle 65 95 bridges the distance from the channels 52 to a channel 66 joining the front edges of the opposite plates 40.

The surroundings of the brush 5 are completed by an adjustable front housing 100 plate 70 and end plates 72, pivoted at 71 to lugs on the plates 40 and held in place by vertically adjustable stops 73. The front section of the housing may be lowered for access to the brush, and to adjust 105 the space 74 into which the doffer-brush centrifugally throws the lint into the air flowing into the lint-trunk 50.

The front lip of the housing plate 70 is made adjustable by an air-regulator plate 75 110 of angular cross-section having one wing adjustably fastened to the plate 70, as by thumb-bolts 76 in slots in plate 70, the other wing extending downwardly and forwardly from a point in the angle between the grate-fall 9, 11, and saws 10, preferably far enough 115 to receive upon its surface the stream of seeds falling from the breast.

It is desirable as usual to provide for the adjustment of the gin-grate 9 in respect to 120 the saws; to provide for temporarily lifting the breast as a whole to take the material in the roll-box out of range of the saws; and in addition it is desirable to provide means for taking the breast structure 6, 8, 9, 11, 125 16 out of the way in order to inspect or remove the saw cylinder.

In the usual practice, the breast is pivoted at the top, for instance by bringing the board 16 to the member 1^d. In the present 130

structure, the breast is pivoted at 80 on short studs sliding in sector slots 82 in brackets 81, which may be integral with or attached to the front uprights 1. Slots 82 5 are central on the point of contact 83 between board 16 and member 1° when the breast is in normal position, Fig. 1. Studs 80 take into bearings 84 attached to the seed-board 11, the remainder of the grate-fall or 10 movable breast being fast to the boards 11 and 16.

The adjustment of the operative position of the grate and the material being operated upon toward and away from the saw shaft 15 2 is effected by positioning the pivots 80 in their slots 81, for instance by adjusting the limit-screws 85 in lugs 86 on the brackets 82.

To lift the breast away from the saws, one or both of the pivot studs 80 is provided 20 with a handle 96 and cam 87 rigid therewith, adapted to react with a roll 88 on bracket 82 to lift the pivot and the bottom of the breast by moving pivot 80 outwardly in slot 81. Cam 87 may be provided with a notch 25 89 to take over roll 88 at the maximum displacement of the pivot and breast. Gravity holds the loaded breast when the handle 86 is operated against the member 1°, the breast turning about the point 83 as a pivot.

30 The whole breast structure is by these arrangements free to be turned about the pivots 80 into the position shown in Fig. 2, in order to remove, clean or sharpen the saws. Heretofore much good seed cotton 35 has been wasted by having to dump the contents of the roll-box in the breast whenever the breast is taken off to get at the saws. To avoid this, the breast-hopper 17 is preferably provided with a hinged front-board 40 18 adapted to turn over and cover the opening into the roll-box. Board 18 may be held in place by any suitable catch, such as the spring catches 19 entering holes in the ends of board 18.

45 In front of the seed board 11 a seed deflector 90 hinged to the front board of the breast may be arranged as shown, to cause the seed to fall through an intake air current passing beneath the seed board 11 and 50 above the front air-regulator plate 75.

The operation of the machine will now be apparent. The saw cylinder, running at any desired speed, usually about 550 R. P. M., takes the lint into its teeth when pulling it 55 from its attachments at grate 9, or carries it with the saws and near them either by travel in the air moving by friction with the saws, or by electrical attraction. The relatively heavy motes are thrown off centrifugally into the space 28, the mote deflector 20 being set with its point between the stream of lint travelling with the saws and the stream of motes thrown therefrom. This separation is distinct and thorough.

60 65 The lint is aided to travel with the saw

by the suction current induced by trunk 50, which places the region of the chamber 28 under a slight vacuum. The action of this current can be regulated by adjusting damper 33.

70 The motes are prevented from mingling again with the lint by deflector 20, and are removed from the machine by conveyor 30.

The action of the brush 5 will now be apparent. The only air moving with the brush is that frictionally engaged by its surface and tufts, and upon the sector of the brush approaching the saws and lying within casing 37 and under deflector 20 there is no air-inlet, so that the slight vacuum induced by the brush in this space is filled up from chamber 28, if from anywhere; on the sector of the brush following engagement with the saws, the suction air-current into trunk 50 exceeds the effort of the brush to 80 fan a current of air.

The action of the tufts of the brush on the lint to be doffed is then purely mechanical and results in clearing more deeply than heretofore the space between the saws of 90 the lint travelling in this space, and throwing off centrifugally all of the lint affected by the brush into the space 74 at and within the suction-passage leading into trunk 50.

95 The incoming air for duct 50 is in part taken through chamber 28, in a greater part through the spaces between the grate-ribs and the saws, and in a still greater part enters between the seed deflector 90 and the regulator 75, passing under the seed board 100 11, and through the falling stream of seed. Detached fiber returned to the roll-box by the saws, or never removed from the roll-box on the saws, is stripped from the seed at this passage. It will be observed that 105 every part of the material is subjected to this gathering current of air.

When the saws, or the brush, or both, are worn by use, the shaft 3 may be adjusted 110 with respect to the concave 37 to maintain the relation of the brush to the concave, and the plates 40 lifted to position the trunk 50, the plate 70, the concave 37, and the brush 5 properly in relation to the new diameters of saw, or brush, or both. The useful life 115 of a brush is greatly increased by this provision.

The trunk 60 may be a conduit shared in common by any desired number of gins, and may deliver into any desired form of 120 condenser.

What I claim is:

1. A gin having therein primary fiber separating means in combination with a rotary doffer brush having its bristles disposed in axially spaced, annular rows, and means exterior to the gin for inducing a lint-conveying air-current into and through the gin, and with means cooperating with the primary separating means and said air- 125 130

- current to separate the motes and the good lint at a point in the travel of the latter prior to its engagement by the doffing means.
- 5 2. A saw gin having therein the usual grate-fall and saws whereby the material to be ginned is mechanically held in contact with the saws, a rotating doffer brush having its bristles arranged in axially spaced, 10 annular rows, said brush being arranged beneath the saws, means between said grate-fall and brush for deflecting centrifugally ejected motes, means providing a lint discharge passage at that portion of the brush 15 opposite said mote deflector, and means for creating a partial vacuum in said passage.
3. A saw gin having therein the usual grate-fall and saws, whereby the material to be ginned is mechanically held in contact 20 with the saws, a rotating doffing-brush beneath the saws, and having deep engagement with the latter and a casing for the saws and brush, a lint trunk leading therefrom, and means independent of the brush 25 for inducing a negative pressure relation to the atmosphere in the lint trunk, whereby to cause an inflow of air into all openings in the casing, and thence into the lint trunk.
- 30 4. Mechanism for separating useful fiber from seeds, comprising a grate, a seed-board, a saw cylinder, and a doffer brush for doffing the fiber from the saw cylinder, in combination with means independent of air currents created by the doffer brush for establishing a flow of air in a direction substantially opposite to the current of denuded seeds flowing over the seed-board and out of the gin and in opposition to the travel 40 of the periphery of the saw cylinder at entrance to the grate.
5. A gin having therein a saw-cylinder and grate, an enclosed space back of these parts into which motes may be thrown from the saw-cylinder, a mote deflector within 45 said space, doffer means for stripping fiber from the saws, and means independent of said doffer means for causing a suction current of air to flow from said space into the interstices between the saws and means for regulating the flow of said air-current.
6. A gin having therein a saw-cylinder and grate, an enclosed space back of these parts into which motes may be thrown from the saw-cylinder, a mote deflector within 55 said space, doffer means for stripping fiber from the saws, and means independent of said doffer means for causing a suction current of air to flow from said space into the interstices between the saws, and means for regulating inflow of air into said space.
7. A gin having therein in combination 60 rotary means for separating the fiber from its attachments, a rotary doffing-brush for removing the fiber from said separating means, an enclosure for these parts having an adjustable inlet opening, means for deflecting motes thrown centrifugally from said rotary separating means away from said brush and into said enclosure and 70 means for inducing the flow of air inwardly through said opening.
8. A gin having therein a grate, a saw, and means for doffing fiber from the saw acting at a distance from the grate, in combination with means for establishing an air-current toward the saws between the grate and doffing means a mote deflector adapted to stand between the good fiber traveling with the saw and the motes centrifugally 75 thrown therefrom at a point between the grate and the doffing means, and means for adjusting the position of said mote deflector.
9. A gin having therein a grate, a saw, and means for doffing fiber from the saw 80 acting at a distance from the grate, an enclosure for these parts, and means for causing a regulated flow of air therein toward the saw in combination with a mote deflector, in said enclosure, adapted to stand between the good fiber traveling with the saw and the motes centrifugally thrown therefrom at a point between the grate and the doffing means, and means accessible from the exterior of said enclosure for adjusting 85 the position of said mote deflector.
10. A gin having therein a grate for supporting the lint-bearing seed, a saw cylinder rotating in contact with the seed on the grate, and a doffing brush in peripheral 90 contact with the saw cylinder rotating at a peripheral speed exceeding that of the saw cylinder, in combination with means interposed between the grate and the doffing-brush for receiving and deflecting motes 95 centrifugally thrown from the saw cylinder, and pneumatic means independent of said brush for delivering the lint stripped from the saws by the brush from the machine.
11. A gin having therein a grate, a rotary 100 saw-cylinder, a casing beneath the saw-cylinder, a doffing-brush rotating in deep engagement with a part of the periphery of the saw remote from the grate and within the casing, a delivery passage for lint leading past the periphery of the brush, and means independent of said brush for inducing a suction current in said passage, in combination with means interposed between the grate and the brush for receiving and 115 deflecting from the brush motes thrown off by the saw-cylinder.
12. A gin having therein a saw-cylinder, a mote deflector adapted to enter between good lint traveling with the saws and motes 120 centrifugally thrown from the saws, and means for establishing a regulated flow of air toward the saws in opposition to the direction in which the motes are thrown.
13. A gin having therein a saw-cylinder, 125

- a mote deflector adapted to enter between good lint traveling with the saws and motes centrifugally thrown from the saws, a back-seal enclosing the saws and the mote-deflector, and providing a receptacle for the motes, and means for establishing a regulated flow of air through said enclosure and toward the saws in opposition to the direction in which the motes are thrown. 55
10. 14. A gin having therein in combination a grate, a saw-cylinder, and a rotary doffer-brush having tufts in relatively continuous annular series, whereby to operate with little air resistance, a casing defining a passage 60 leading under the saw-cylinder and brush, and means independent of the brush for inducing in said casing a draft of air away from the gin.
15. In a saw gin, a grate, the combination 65 of a saw-cylinder, and a doffer-brush working on one side of the grate, and a chamber into which the doffer-brush throws lint stripped from the saws, with means for maintaining a suction current of air into 70 and through said chamber having inlets on said side of the grate.
16. A saw gin having therein a saw cylinder, a doffer-brush, and a lint-trunk, and means for simultaneously adjusting the lint-trunk and brush toward and away from the saw-cylinder. 75
17. A saw gin having therein a saw-cylinder, a doffer-brush therefor, means for impeding flow of air about the periphery of 80 the doffer-brush on the side opposite the saw-cylinder, and means for adjusting said brush and impeding means in respect to the saw-cylinder.
18. A saw gin having therein a saw-cylinder, a doffer-brush therefor, means for impeding flow of air about said brush on the side opposite its point of contact with the saws, and a suction lint-trunk having an 85 opening on the delivery side of said brush.
40. 19. A saw gin having therein a saw-cylinder, a doffer-brush therefor, means for impeding flow of air about said brush on the side opposite its point of contact with the saws, and a suction lint-trunk having an 90 opening on the delivery side of said brush, and means for adjusting the position of the brush, impeding means and lint-trunk in 95 relation to the saw-cylinder.
50. 20. In a gin, means for adjusting the parts to take up wear comprising slides mounted on the frame, means for positioning the slides, a doffer-brush having bearings mounted on the slides, and a lint-trunk having one end mounted on and movable with the slides. 100
21. In a gin, means for adjusting the parts to take up wear comprising slides mounted on the frame, adjusting screws for positioning the slides, a doffer-brush having bearings adjustably mounted on the slides, and a lint-trunk having one end mounted on and movable with the slides. 105
22. A gin having therein a rotary doffer-brush, a lint-trunk comprising a section having one end mounted on movable slides 110 also carrying bearings for the doffer-brush, and having an adjustable connection between said section and another section of the lint-trunk mounted on the machine frame. 115
23. A gin having therein a rotary doffer-brush, adjustable slides carrying bearings for said brush and a section of a lint-trunk into which said brush delivers, and having a housing plate continuing one wall of the 120 lint-trunk and defining with the surface of said brush an entrance chamber for the lint-trunk. 125
24. A gin having therein a rotary doffer-brush, adjustable slides carrying bearings 130 for said brush and a section of a lint-trunk into which said brush delivers, and having a housing plate adjustable with and angularly adjustable upon said slides, and continuing one wall of the lint-trunk and defining with the surface of said brush an entrance chamber for the lint-trunk. 135
25. A gin having therein a grate, and seed-board, a saw-cylinder, a rotary doffer-brush, and a suction lint-trunk, and having 140 means for inducing an inflow of air through the discharged seeds and past the saws comprising a plate continuing the lower edge of a suction-trunk leaving the space beneath the doffer-brush, means for adjusting the 145 rotative position of said plate in respect to its juncture with said trunk, and adjustable means at the front edge of said plate for controlling the inflowing air-current in respect to the seed-board and saw-cylinder. 150
- Signed by me at Dallas, Texas, this 14th day of August, 1919.

ARTHUR A. VARDELL.
